(57) **CLAIM**

The ornamental design for a misting port apparatus, as shown and described.

DESCRIPTION

FIG. 1 is an isometric view of a jet misting port apparatus hereof;

FIG. 2 is a top plan view of a jet misting port apparatus according to FIG. 1;

FIG. 3 is a bottom plan view of a jet misting port apparatus according to FIG. 1; and,

FIG. 4 is a front elevational view of a jet misting port according to FIG. 1 (all of the left and right side and the back elevational views are substantially the same as this front elevational of FIG. 4).

FIG. 5 is an isometric view of a turbulence-inducing misting port apparatus hereof;

FIG. 6 is a top plan view of a turbulence-inducing misting port apparatus according to FIG. 5;

FIG. 7 is a bottom plan view of a turbulence-inducing misting port apparatus according to FIG. 5; and,

FIG. 8 is a front elevational view of a turbulence-inducing misting port apparatus according to FIG. 5 (all of the left and right side and the back elevational views are substantially the same as this front elevational of FIG. 8).

The design is a misting port for mixing of air and water intended for cooling and heating air distribution. The jet model provides for air flow therethrough in a jetting fashion and the turbulence-inducing model provides a slight deflection added to the web to create turbulence that aids in the mixing of air and water.
